AUTOMOBILE DOOR LATCH STRUCTURE

Holden W. Rightmyer, Toledo, Ohio, assignor to
The American Swiss Company, Toledo, Ohio, a
corporation of Ohio

Application December 21, 1936, Serial No. 116,925

2 Claims. (Cl. 292—169)

This invention relates to door latches particularly for automobiles and an object is to produce a latch of this character which is simple in construction, inexpensive to manufacture, reliable in operation, and has the new and improved features of construction hereinafter described.

One embodiment of the invention is shown for purposes of illustration, on the accompanying drawing, in which

10 Figure 1 is a side elevation of a door latch embodying the invention;

Fig. 2 is a front edge view of the latch shown in Figure 1;

Fig. 3 is a side edge view of the latch;

15 Fig. 4 is an enlarged fragmentary elevation of a portion of the latch showing the relation between the latch bolt, roll back and dogging slide;

Figure 5 is a top plan view of the latch bolt, a portion of the bolt nose being broken away; and

20 Figure 6 is a transverse sectional view substantially on the line 6—6 of Figure 1.

The illustrated embodiment of the invention comprises a door latch having a case plate 10 provided at its front edge with an outwardly extending flange 11 through which the nose of the latch bolt 12 extends. The latch bolt is generally of Z shape and consists of an upper horizontal portion 13 which includes a bolt nose 14 secured by rivets 15 to a bolt plate 16. Integral with the 25 horizontal upper portion 13 is a downwardly extending or vertical portion 17 which extends inwardly to abut closely against the case plate 10. Integral with the portion 17 and extending rearwardly therefrom substantially in parallel relation to the upper horizontal portion 13 is a lower horizontal portion 18, the rear end of which, when the latch bolt is in latching position, is substantially flush with the rear edge of the case plate 10. For retracting the latch bolt from the 30 outside of the door is a roll back 19 having an arm 20 engageable with a shoulder 21 on the vertical portion 17 of the latch bolt. The roll back 19 is disposed close to the case plate flange 11 and is provided with a square opening 22 to receive the handle shank (not shown). Extending rearwardly from the roll back 19 is a finger 23 which is integral with and moves with the roll back and is disposed beneath an embossed portion 24 of the bolt plate, thereby to enable free rocking 35 movement of the finger. On the other side of the roll back away from the retracting finger 20 is a finger 25 which is adapted to be blocked by a slide 26 actuated by an eccentric cam 27 which has a square opening 28 to receive a suitable operating shaft usually operated by a key controlled

cylinder lock (not shown). The slide 26 and associated parts are carried by a suitable mounting plate 29.

Disposed between the horizontal portion 18 of the latch bolt and the case plate 10 is a dogging slide 30, the rear end of which extends outwardly from the case plate 10 and is adapted to be operated by a suitable remote control mechanism actuated from the inside of the door as will be readily understood by those skilled in this art. 10 The forward end of the slide 30 is provided with a nose or cutout portion 31 to fit beneath the finger 23 when the slide is moved forwardly, thereby to prevent rocking or turning movements of the roll back 19. The slide 30 is provided with a horizontal elongate slot 32 into which projects a tongue 34 integral with the horizontal portion 18 of the latch bolt, thereby affording the lost motion necessary to move the slide 30 forwardly into roll back blocking position. The slide 30 is 15 slidable on a pair of parallel laterally spaced elongate raised portions or ridges 36 integral with the case plate 10, thereby to reduce the frictional engagement between the slide and case plate as much as possible. Interposed between the lower 20 horizontal portion 18 of the latch bolt and the slide 30 and providing spacers therebetween are buttons 37, two rows being provided in parallel laterally spaced relation.

For holding the parts in position, and for guiding the movement of the latch bolt is a cover plate 38 which has at its forward end an upwardly embossed portion 39 which provides a bearing for the roll back 19 and has a squared opening 40 axially aligned with the opening 22 in the roll back. It will be observed that the width of the dogging slide 30 and the lower horizontal extension 18 is substantially the same. The cover plate 38 is thus designed to fit over these two parts and snugly embraces them to hold them in their proper relation. The cover plate has opposite 30 depending side walls 41 and on the lower side are tongues 42 which extend through apertures in the case plate 10 and are bent outwardly against the under side of the case plate, substantially as 35 shown. A tongue 43 on the upper side of the cover plate similarly extends through an aperture in the case plate and is bent outwardly against the rear face thereof. It will be observed that a spiral spring 44 has one end anchored to the 40 case plate and the opposite end engages the rear end of the bolt nose 14 for normally urging the latch bolt to latching position.

A cardinal feature of this invention resides in the features of construction and arrangement of 45

the door latch particularly with a view of providing a very inexpensive structure which can be easily manufactured and assembled on a commercial or production basis. An important feature is the utilization of a single cover plate which serves for both the roll back 19, the dogging slide 30 and the latch bolt. It will be observed that a substantially straight narrow cover plate can be utilized and this serves not only to hold the parts in their proper relation but also to a large extent serves as a guide for the latch bolt.

Changes in details of construction, arrangement and operation may be effected without departing from the spirit of the invention, especially as defined in the appended claims.

What I claim is:

1. In a vehicle door latch, a case plate, a spring tensioned substantially Z-shaped latch bolt, a roll back for retracting said bolt disposed directly in advance of the lower horizontal portion of the bolt, a finger rotatable with said roll back, a raised portion on said bolt overlying said finger

and shaped to enable rocking movements thereof, a dogging slide between said horizontal portion of the bolt and said case plate and adapted when in one position to block movement of said finger, and a single cover plate fitting over said roll back and said horizontal portion of the bolt, secured to said case plate and providing a guide for movement of said bolt. 5

2. In a vehicle door latch, a case plate, a spring tensioned substantially Z-shaped latch bolt, a roll back for retracting said bolt disposed adjacent the lower horizontal portion of the bolt, a finger rotatable with said roll back, a dogging slide between said horizontal portion of the bolt and said case plate and adapted when in one position to block movement of said finger, and a single cover plate fitting over said roll back and said horizontal portion of the bolt secured to said case plate and providing a guide for movement of said bolt. 10 15 20
